FIG. 1

FIG. 2

FIG. 3

FIG. 5

FIG. 4

FIG. 1 is a front, top and side perspective view of an electronic flash unit, showing my new design;

FIG. 2 is a side elevational view, the opposite side being substantially a mirror image thereof;

FIG. 3 is a top plan view, the bottom being substantially a mirror image thereof;

FIG. 4 is a front elevational view; and

FIG. 5 is a rear elevational view thereof.

Portions of the drawing figures are stippled to indicate contrast in appearance.

The dominant features of my new design are shown in solid lines in the drawing.

Portions of drawing FIGS. 1 and 4 are diagonally lined to indicate transparent portions of the electronic flash unit showing my new design.

I claim:

The ornamental design for an electronic flash unit, as shown and described.
